(57) **CLAIM**

The ornamental design for a projector equipped with a camera, as shown and described.

DESCRIPTION

FIG. 1 is a perspective view of front, top and right side of a projector equipped with a camera showing my new design; FIG. 2 is a perspective view of front, bottom and right side thereof;

FIG. 3 is a perspective view of rear, top and right side thereof; FIG. 4 is a front view thereof;

FIG. 5 is a rear view thereof;

FIG. 6 is a left side view thereof;

FIG. 7 is a right side view thereof;

FIG. 8 is a top view thereof;

FIG. 9 is a bottom view thereof;

FIG. 10 is a perspective view of usage thereof;

FIG. 11 is a perspective view of usage thereof; and,

FIG. 12 is a perspective view of usage thereof.

The broken lines shown are included for the purpose of illustrating the unclaimed portions of a projector equipped with a camera and form no part of the claimed design.
